UNITED STATES PATENT OFFICE.

HENRY HENRICH, OF NEW YORK, N. Y.

MACHINE FOR ROLLING FINGER-RINGS.

1,124,434.

Specification of Letters Patent. Patented Jan. 12, 1915.

Application filed January 30, 1911. Serial No. 605,581.

To all whom it may concern:

Be it known that I, HENRY HENRICH, a citizen of the United States of America, residing in New York, in the borough of Manhattan, county and State of New York, have invented certain new and useful Improvements in Machines for Rolling Finger-Rings, of which the following is a specification.

This invention relates to improvements in machines for rolling seamless finger-rings in which the blanks, which are formed by means of dies, are transformed into completely finished rings of the required size and cross-section, and in which the exact size to be produced is accurately controlled by a visual index so as to permit the removal of the finished ring at the proper time.

The invention consists more specifically of a machine for rolling seamless finger-rings provided with a visual index by means of which the exact size of the finger-ring rolled on the mandrel of the machine is indicated, the special construction of said visual index being fully described hereinafter and finally pointed out in the claims.

In the accompanying drawings, Figure 1 is a front-elevation of my improved machine for rolling finger-rings, partly in section through the supporting table and showing the visual index device, Fig. 2 is a vertical transverse section on line 2, 2, Fig. 1, Figs. 3 and 4 are horizontal sections respectively on lines 3, 3 and 4, 4, Fig. 1, drawn on a larger scale, Fig. 5 is a detail vertical section showing the mandrel and operating rollers and the visual index for rolling a finger-ring of predetermined size, and Fig. 6 is a vertical transverse section on line 6, 6, Fig. 5.

Similar letters of reference indicate corresponding parts throughout the different figures.

Referring to the drawings, A represents the table of my improved machine for rolling seamless finger-rings.

On the table A is supported an upright standard *a*, which is provided with a journal-bearing for a horizontal shaft *s*, on the front-end of which is mounted a grooved ring-forming roller *b* which is continuously rotated by suitable gear-wheel transmission which is applied to the opposite end of the shaft *s* (not shown in the drawings).

On the main-shaft is mounted a gear-wheel *g⁴* which meshes with a pinion *g⁵* on

a short shaft *a³* that is supported in a bracket-bearing *g⁶* which is attached to the upright standard *a*. The pinion *g⁵* meshes with a gear-wheel *g⁷*, the shaft of which also turns in a bearing.

Adjacent to the gear-wheel *g⁷* is arranged a pinion *g⁸* which is keyed to the rear-end of the mandrel-spindle *s⁴*, the front-end of which is provided with a square socket for inserting a mandrel *m* on which the ring-blank is placed. The mandrel-spindle *s⁴* is supported in a sleeve-shaped bearing *m¹* which is provided with a rectangular arm *m⁴* that is bolted to a vertical slide-piece D, as shown in Fig. 2.

The slide-piece D is provided with a dovetailed rear-portion which is guided in corresponding ways *d* on the front-standard *a*, said slide-piece being provided with an extension *D¹* at its lower end that extends through an opening in the table A, and is provided with a counterweight (not shown) that is suspended by means of a rod *w¹* having a hook-shaped upper end from the lower end of the extension *D¹*, as shown in Fig. 2. When the slide-piece D is in its lowermost position of rest the pinion *g⁸* at the rear-end of the mandrel-spindle *s⁴* is out of mesh with the gear-wheel *g⁷*, but when the slide-piece is raised the pinion *g⁸* intermeshes with the gear-wheel *g⁷*, so that rotary motion is imparted to the mandrel-spindle and the mandrel *m* on the front-end of the same.

The mandrel-spindle *s⁴* is provided intermediate of its length with a circumferential groove *m²* that is engaged by a set-screw *m³* for holding the mandrel-spindle in proper position in its sleeve-shaped bearing.

The mandrel *m* is provided with a groove corresponding in size and shape with the ring to be rolled from the blank; different sizes and shapes requiring correspondingly grooved mandrels.

Below the mandrel, in front of the slide-piece D, are arranged two pairs of supporting rollers *n* which support the cylindrical ends of the mandrel. The mandrel is provided with shouldered portions *m^x* adjacent to the ring-carrying groove and between the supporting rollers for increasing the strength of the same and resisting the bending of the mandrel and the shifting of the same in longitudinal direction. The inner end of the mandrel *m* is made of square shape so as to fit in the corresponding socket of the mandrel-spindle. At both sides of

the mandrel are arranged guide-rollers E which are provided with grooves for holding the ring-blank, said guide-rollers being pivoted to the upper ends of laterally oscillating elbow-levers E¹ that are fulcrumed to wing-shaped brackets e attached to opposite sides of the slide-piece D, the lower arms of the levers E¹ extending in outward direction and resting on antifriction rollers r that 10 rest on arms r¹ attached to an auxiliary slide-plate F, and moving with the same so as to move the elbow-levers with the guide-rollers E in inward direction for pressing on the ring-blank, as shown in full lines in Fig. 5 or in outward direction, as shown in dotted lines in the same figure, when the auxiliary slide-plate F and the slide-piece D are lowered for removing the finished ring. The outwardly-extending arms e¹ of the elbow-levers E¹ are connected by helical springs e² with stationary points on the slide-piece D, located below the fulcra of the elbow-levers E¹ so that the guide-rollers are moved away from the ring-blank when 25 the slide-plate F is lowered.

The auxiliary slide-plate F is arranged at the front of the slide-piece D and guided thereon. Centrally thereof is arranged a projecting pin d which is engaged by the 30 inner end of a lever L, which is weighted at its outer end, and which serves to lift the slide-plate F at the proper time. The weighted lever serves for counterbalancing the weight of the slide-plate F and of the 35 parts attached thereto, and facilitates the lifting of the slide-plate so as to bring it from its lower position of rest into the working position. The counter-weight on the hook w¹ on the one hand serves to lower the 40 slide-piece D, while the weighted lever L on the other hand serves to raise the slide-plate F.

For the purpose of indicating the required size of the ring, a horizontal finger f is located below the mandrel and extended 45 over the lower part of the ring-blank, said finger being arranged at the upper end of a vertical rod f¹ that is guided in a vertical bore f² of the slide-piece D, said vertical rod being provided with a forwardly-extending rod f³ which passes through an elongated slot f⁴ in the slide-piece D to the outside of the same and engages the end of an index 50 or pointer i, which is fulcrumed to a sector-shaped scale-plate I that is attached to the upper front-part of the slide-piece D and provided with graduations at its outer arc-shaped end so as to indicate the different sizes of finger-rings to be rolled. As soon 55 as the pointer i arrives at the number corresponding to the size of the ring, the motion of the mandrel-spindle is interrupted, the slide-piece returned to its lower position by turning the crank-shaft d⁴, by which motion the guide-rollers are moved sidewise 60

of the mandrel, owing to the return of the slide-plate by its counterweight and the action of the springs e², so that the completed ring can be removed with the mandrel by removing the latter from its socket. A new 70 blank is then placed on the mandrel and the same returned to its position in its spindle. During the downward motion of the slide-piece into its lowermost position of rest the vertical shank f¹ of the finger f forms contact with a slide-rod k which is located in the bore f² below the shank f¹ and supported on a stationary arm k¹ that is attached to the table A sidewise of the slide-piece D, so that the finger is lifted, together with its 80 horizontal arm f³, and placed into a position close to the mandrel, while the pointer is returned to the starting point on the scale, as shown in Fig. 1. The scale-plate I is provided with an arc-shaped slot i¹, concentric 85 with the fulcrum of the pointer i, by which the scale-plate may be adjusted on its clamping screw i² slightly higher or lower so as to permit the adjustment of the scale-plate to different sizes or ring-blanks. After the 90 scale is adjusted and the pointer set to the proper graduation on the scale, the latter is clamped in position by the clamping screw and the special size of rings rolled until the desired quantity of the rings of a certain 95 size is obtained.

The rolling of the blank into a finger-ring of the proper size is accomplished in the same manner as in finger-ring rolling machines heretofore in use, and requires no 100 special description in addition to the operation hereinbefore described in connection with the rolling parts of the machine.

The new and important feature of this invention resides in the size-indicating scale 105 and index, as the rolling of the ring to the proper shape is accomplished by the automatic rolling devices which are more specifically described in the pending application for an improved machine for rolling finger-rings, Serial No. 564,635, filed June 2, 1910, from which this application is divided out.

The advantage of the improved construction for rolling finger-rings is that the size-indicating scale and index-finger indicate 115 the exact moment when the blank has been rolled to the required size of the ring, so that the motion of the rolling parts can be immediately interrupted as soon as the index-finger or pointer arrives at the number 120 corresponding with the size of the ring to be rolled.

Having thus described my invention, I claim as new and desire to secure by Letters Patent:

1. In a machine for rolling finger-rings, the combination of a mandrel, a slide-piece, a finger adapted to engage the inside of the ring-blank, while the latter is on the mandrel, a vertical shank for said finger, a slide- 125

130

- rod guided in the slide-piece, and a stationary support for said slide-rod for raising the finger-shank when the slide-piece is lowered.
- 5 2. In a machine for rolling finger-rings, the combination of a mandrel, a finger adapted to engage the inside of the ring-blank, a vertical shank for said finger, a slide-piece for supporting the mandrel with 10 ring-blank and provided with a vertical bore in line with the finger-shank, a slide-rod in said bore below the finger-shank, and a stationary support for said slide-rod, said rod raising the finger-shank when the slide- 15 piece is lowered.
3. In a machine for rolling finger-rings, the combination of a ring blank supporting mandrel, a vertically guided slide-piece having a guide-slot in its upper part and 20 supporting the mandrel, a finger below the mandrel and adapted to engage the inside of the ring-blank, a vertical shank for said finger, a horizontal arm extending forward
- from said shank through said guide-slot, a scale, and a fulcrumed index or pointer engaged by said forwardly-extending arm for moving the pointer over the scale and indicating the size of the ring.
4. In a machine for rolling finger-rings, the combination of a ring blank supporting 25 mandrel, a vertically guided slide-piece having a guide-slot in its upper part and supporting the mandrel, a finger below the mandrel and adapted to engage the inside of the ring-blank, means for raising the finger by 30 the lowering of the slide-piece, a scale, means for adjusting the scale, and a fulcrumed pointer adapted to move over the scale and indicate the size of the ring.

In testimony, that I claim the foregoing 35 as my invention, I have signed my name in presence of two subscribing witnesses.

HENRY HENRICH.
